CROWN THROAT

James Kantor, Chicago, Ill., assignor to The
Liquid Carbonic Corporation, Chicago, Ill., a
corporation of Delaware

Application October 20, 1930, Serial No. 489,777

6 Claims. (Cl. 226—86)

The present application relates to crown throats for bottle crowning machines, and the primary object thereof is to provide a throat which shall be of such character as to avoid substantially all possibility of breaking bottles because of excess size of the necks, and further to provide a throat of such character as to permit easy release of the crowned bottle mouth. Further objects of the invention will appear as the description proceeds.

To the accomplishment of the above and related objects, my invention may be embodied in the form illustrated in the accompanying drawing, attention being called to the fact, however, that the drawing is illustrative only, and that change may be made in the specific construction illustrated and described, so long as the scope of the appended claims is not violated.

In said drawing,

Fig. 1 is a partial section of a portion of a bottle crowning machine embodying the throat of the present invention;

Fig. 2 is a side elevation of the throat;

Fig. 3 is a plan thereof;

Fig. 4 is a side elevation, partly in section, of one element of the throat; and

Fig. 5 is a similar view of another element of the throat.

In the operation of bottle crowning machines, a problem that is always encountered is created by the fact that the mouths or necks of bottles are not absolutely uniform in size. According to established practice, the mouth of a bottle, having a cap loosely mounted thereon, is forced into a throat, either by movement of the bottle, or by movement of the throat, the internal diameter of the throat being such as to crimp the rim of the cap about the bead provided on the bottle. If the bottle mouth is oversize, and if the throat is rigid, obviously the bottle will be broken.

Another difficulty experienced in the operation of the bottle crowning machines has to do with the removal of the bottle mouth from the throat after the crown has been crimped thereon. A spring pressed plunger is usually provided for forcing the bottle mouth out of the throat, but obviously it is desirable to use as light a spring as possible for this operation. As obviously, if a rigid throat is used, a heavy spring must be provided to force the bottle out of the throat.

Both of these difficulties have been overcome by the construction illustrated in the accompanying drawing. Referring more particularly to the drawing, it will be seen that I have illus-

trated a portion 10 of a crowning machine, said portion carrying what may be termed a base member 11, said member being formed with an aperture 12 in its lower surface. Preferably a guide plate 13 formed with an aperture 14 registering with the aperture 12 is secured to said base member, said guide plate being provided with a plurality of guide fingers 15, in accordance with previously known practice. The machine is preferably provided with a channel 16 through which caps 17 are supplied.

An element 18 of the machine is formed with a bore coaxial with the aperture 12, and in said bore there may be mounted a bushing 19 in which is slidably mounted a plunger 20. The plunger is preferably provided with a collar 21 integral therewith, or rigidly secured thereto, upon which bears a compression spring 22. The lower end of the plunger 20 may carry a head 23 which may be one of an interchangeable set.

According to the present invention, there is mounted between the element 18 and the lower portion of the base member 11 a crown throat comprising an annular element 24 formed with a substantially cylindrical inner surface 25, and made up of a plurality of segments 26. The outer surface of the annulus 24 is formed as an upwardly tapered frusto-conical surface 27. The bushing 19 may enter the bore of the member 24 to center the same and to position said annulus 24 in coaxial relation with the aperture 12.

The crown throat also comprises a second annulus 28 formed with an inner upwardly tapering frusto-conical surface 29 conforming to the shape of the surface 27 of the element 24. The annulus 28 is likewise made up of a plurality of segments 30, the lines of juncture between said elements 30 coinciding with the lines of juncture between the elements 26 of the annulus 24. Resilient means are provided for resisting radial expansion of the annulus 28, and I prefer to use a helical spring, such as is illustrated at 31 in the drawing. Obviously, a plurality of radially expandable spring rings might be used, or a single spring of any desired characteristics might be used, in place of the helical spring 31.

Threadedly secured to, and depending from, the element 18 is an annular guide member 35 formed with an inturned flange 36 defining a guide aperture 37, the internal diameter of which is substantially greater than the external diameter of the spring 31. Said guide element is operative to prevent complete misalignment of the crown throat with the aperture 12, while permitting sufficient shifting thereof to accom-

modate the throat to the necks of bottles which are introduced thereto.

While the operation of the disclosed device will be obvious, it may be summarized as follows. A 5 cap 17 being positioned as shown in the aperture 12, the mouth of a bottle is forced upwardly through the aperture 14 and into cooperative relation with the cap 17. As the bottle is forced farther upwardly, the cap comes into contact with the 10 head 23 and the plunger 20 is moved upwardly against the tendency of the spring 22, thus compressing said spring. As the cap 17 enters the bore 25 of the element 24, the rim of said cap is crimped about the bead on the bottle, it being 15 obvious that, if the bottle is oversize, the segments of the annuli 24 and 28 will be separated, overcoming the tendency of the spring 31, whereby by the bore 25 of the element 24 is expanded. After the cap has been crimped in place, the supporting element for the bottle is allowed to fall 20 and the spring 22 tends to move the plunger downwardly. Such movement of the plunger forces the bottle also downwardly and, because of the frictional engagement of the cap with the 25 annulus 24, and because the annulus 24 is proportioned as shown, said annulus is also caused to move downwardly until its base 32 comes into contact with the base member 11. As will be 30 obvious, such movement of the annulus 24 moves the surface 27 thereof out of contact with the surface 29 of the annulus 28, thus freeing the annulus 24 from the effect of the spring 31, and permitting expansion of the annulus 24 to permit a free removal of the bottle mouth therefrom.

35 I claim as my invention:

1. As a new article of manufacture, a crown throat comprising a segmental annulus having its outer periphery tapered substantially throughout its length, a second segmental annulus surrounding said first annulus and having its inner periphery tapered substantially throughout its length to correspond to the external shape of said first annulus, said annuli being normally out of contact with each other, and means associated 45 with said second annulus and resiliently retaining the segments thereof in engagement with each other.

2. As a new article of manufacture, a crown throat comprising a radially expandable annulus 50 having its outer periphery tapered, the interior dimensions of said annulus being the same from end to end to present an unobstructed opening therethrough, a second radially expandable annulus surrounding said first annulus and having its inner periphery tapered to correspond to the external shape of said first annulus, and means 55 associated with said second annulus and resiliently retaining the same in its condition of maximum contraction, said first annulus being axially movable into and out of a position wherein expansion thereof is resisted by said resilient means.

60 3. In a bottle crowning machine, a base having an aperture therethrough, a crown throat sup-

ported on said base in registry with said aperture, a spring-pressed plunger normally disposed in said throat and adapted to be moved against the tendency of its spring by the projection of the mouth of a bottle into said throat, said throat comprising a radially expandible element, means resiliently resisting expansion of said element during spring-compressing movement of such bottle, and means interposed between said first-named means and said element and operable to prevent said resilient means from opposing expansion of said element during movement of such bottle in the opposite direction.

4. In a bottle-crowning machine, a crown throat comprising a radially expandible element 15 having an opening therethrough of the same dimensions from end to end adapted to receive the mouth of a bottle to clamp a cap thereon, means resiliently resisting expansion of said element during relative movement of said throat and bottle mouth in one direction, and means automatically operative, during relative movement thereof in the opposite direction to render said first-named means ineffective to resist such expansion.

5. In a bottle crowning machine, a base having 25 an aperture therethrough, and a crown throat supported on said base, said throat comprising a radially expandible element resting on said base, means associated with said element and resiliently resisting expansion thereof, said element 30 having its inner surface tapered upwardly, and a second radially expandible element formed with a socket registering with said aperture and having its outer surface tapered upwardly to correspond to the inner surface of said first element, 35 said second element being of such dimensions that its external surface engages the internal surface of said first element only when said second element is lifted out of contact with said base.

40 6. In a bottle crowning machine, an apertured base, a guide concentric with the aperture in said base, and a crown throat supported on said base and guided by said guide, said crown throat comprising an outer annulus made up of a plurality of segments normally held in mutually contacting relation by a contractile spring surrounding said annulus, said segments cooperating to form an upwardly tapering annular internal surface, and the external circumference of 45 said spring being substantially less than the internal circumference of said guide; and an inner annulus made up of a plurality of cooperating segments, said segments forming, when in mutually contacting relation, an annulus having an 50 upwardly tapering external surface and a substantially cylindrical internal surface defining a bore having a diameter equal to the diameter of a bottle cap after crimping; the external surface of said inner annulus, when said inner annulus is resting on said base, being spaced from the internal surface of said outer annulus.

JAMES KANTOR.
